UNITED STATES PATENT OFFICE.

EDWARD BUCKMASTER ROBINSON, OF BRENTWOOD, ENGLAND, ASSIGNOR TO SULLIVAN MACHINERY COMPANY, OF CHICAGO, ILLINOIS, A CORPORATION OF MASSACHUSETTS.

MINING APPARATUS.

Application filed February 4, 1926, Serial No. 85,913, and in Great Britain October 13, 1925.

This invention relates to mining apparatus and comprises improvements in wheeled trucks or trolleys for mining machines.

In the specification of the co-pending

- 5 United States application Serial No. 723,953, filed July 3rd, 1924, in the name of Morris P. Holmes, there is described a truck on which a mining machine of the swinging jib type can be loaded and supported either 10 on its top or bottom so that it can be used for over-cutting or under-cutting and while in either position the machine can effect truck propulsion through the medium of a clutch which serves to connect the feed-chain 15 sprocket with the truck propulsion gear.

The present invention has for its main object to provide an improved construction of truck on which the machine can be loaded and supported on its top, bottom or side so 20 that it can be used for over-cutting, under-cutting or shearing without materially increasing the overall height of the mounted machine when in its shearing position, while at the same time enabling the machine to 25 effect truck propulsion when in any of its positions on the truck.

According to this invention, therefore, there is provided in a mining machine truck the combination with horizontal supports 30 which support the machine in a working position in which it lies on its bottom or top lengthwise on the truck, of another horizontal support which is at a lower level than that of the other supports and is between them 35 and can support the machine when it is horizontal but on its side. The track platform may be provided with a longitudinal channel or recess to receive and support the machine on its side so that the jib can swing 40 in a vertical plane for shearing, while the portions of the platform on either side of the channel serve to support the machine on its top or bottom so that the jib can swing in different horizontal planes for over-cutting. 45

Preferably the truck is provided with propelling gear which is so arranged as to be directly engageable with a driving member on the machine when the machine is in any one 50 of its aforesaid positions on the truck. For a machine having a driving member situated on its central longitudinal axis, as in the aforesaid prior application the channel or recess may be of such a depth that the ro-

tational axis of the said driving member 55 will be in line with the rotational axis of a driven member on the truck when the machine is on its side in the channel for a purpose which will be described.

Other features of the invention will be 60 hereinafter described and pointed out in the claiming clauses.

Referring now to the accompanying drawings which show a truck for a coal cutting machine of the swinging jib chain 65 cutter type:

Figure 1 is a side elevation of the truck, partly in section, and showing in chain dotted lines, the machine in shearing position thereon.

Figure 2 is a plan of the truck with the machine removed for clearness.

Figure 3 is a sectional end elevation on the line III—III of Figure 1.

Figure 4 is a side elevation of a modified 75 form of truck.

Figure 5 is a detail sectional view of a portion of the truck propulsion drive showing the clutch part thereon.

Figure 6 is a detail sectional view of the 80 cooperating clutch part on the machine feed chain sprocket.

Figure 7 is a face view of the clutch part shown in Figure 6.

The truck comprises a guiding frame or 85 platform 1 mounted on track wheels 2 secured to axles 3 journalled in the usual manner in axle boxes 4, and is adapted to run on the rails 5. The platform 1 is provided with a central longitudinal channel or recess 6 90 the bottom 7 of which provides a support or platform at a lower level than the platform 1 to support the machine 8 on its side. Obviously this platform may be built up of a skeleton framework with suitable guides or 95 supports to take the machine instead of the solid walled construction shown. The channel is of a suitable width to take the machine on its side, and in the construction of truck illustrated, which is intended for a mining 100 machine having a feed-operating-member 9 situated on the central longitudinal axis of the machine (for example a machine of the type described in British Patent No. 211,473) the channel is of such a depth that the said 105 axis lies in the same horizontal plane when the machine is on its side as when on its top or bottom as clearly illustrated in Figure 3.

This is for a purpose hereinafter more fully described.

In order that the machine may be firmly secured to the truck so that cutting may be effected while the machine is in position thereon, suitable clamping devices may be provided. As shown, for clamping the machine in its shearing position a pair of yoke clamps 10 are provided which are adapted 10 to embrace the machine. These clamps are each provided with a clamping screw 11 adapted to be manipulated by means of a tommy bar, and are each pivotally secured at 12 within the channel 6 so that they may 15 be folded down to lie below the level of the platform 1 when it is required to load the machine thereon. The clamping screws 13 are adapted to engage recesses 14, (shown in Figure 4) which are provided in a machine of the type hereinbefore referred to, for accommodating the securing bolts holding the sections of the machine together.

In order that the machine may be loaded to and unloaded from either the upper or 25 lower platforms a detachable slide 15 is provided. This slide may be centrally dished as shown at 16 to provide a guide way for the machine when on its side. Hinge lugs 17 and 18 are provided on the upper and 30 lower platforms respectively of the truck so that the slide can be pivotally secured to cooperate with either platform as desired. The slide may have a rearwardly extending tongue 19 whereby it is raised when the machine is loaded and which serves to steady the lowering of the machine during unloading. This tongue is conveniently situated 35 within the channel 6 as shown. It will be understood that the machine may haul it self up the incline and on to either platform as desired by means of its feed chain.

The truck propulsion gear may be similar to that described in the said prior application Serial No. 723,953, and comprises a 45 horizontal shaft 20 having a clutch part 21 thereon for cooperation with another coacting clutch part 22 on the feed operating member 9 on the machine. The shaft 20 is connected by suitable gearing, preferably 50 including reverse bevel gearing which may be situated in the casing 23, to the transverse shaft 24 which is geared to the shaft 25 carrying a sprocket wheel 26 which is coupled by means of the driving chain 27 to a 55 sprocket 28 on the axle 3 of the rear pair of track wheels 2. The drive may be transmitted also to the axle of the front pair of wheels by means of sprockets 29, 30 and the connecting chain 31. A brake 32 is shown 60 on the transverse shaft 24.

Referring now to Figures 5, 6 and 7 which show a modified form of clutch according to this invention, it will be seen that the clutch part 21' on the shaft 20 is slidably 65 mounted on the splined end 33 of the said

shaft and a spring 34 between the casing 23 and the said clutch part tends to maintain the latter in the position shown. The face of this clutch part is provided with four recesses 35 and a conical guide hole 36 terminates in a central hole 37 to receive a guide pin 38 (Figure 6) carried on the machine and projecting from the end of the driving shaft 39 on which is mounted the feed-operating sprocket 9 and the second clutch part 22' mounted thereon. The face of this second clutch part is provided with four projections 40 which are adapted to engage the aforesaid recesses 35 on the other clutch part 21'. It will be seen that when the machine is moved endwise during loading on the truck to engage the truck propulsion gear, the guide pin 38 will engage the parts 36 and 37 and bring the shafts 20 and 39 into line. If the projections 40 are not 80 opposite the corresponding recesses 35 the clutch part 21' will be forced back against the action of the spring 34, and thus when the shaft 39, and with it the clutch part 22', is rotated by the machine motor, as soon as 85 the clutch projections and recesses come opposite one another the clutch part 21' will be forced out by the spring into operative engagement with the part 22'. The part 21' being spring mounted as described also acts 90 as a buffer for the machine.

The rotational axis of the feed operating member 9 being arranged as herein described in the central horizontal and also in the central vertical plane of the machine and the channel in the truck being arranged as described, it will be seen that after change in position of the machine upon the truck to change the plane of cut of the swinging cutting jib 42, the position of the aforesaid rotational axis remains the same and thus the shaft 39 on the machine can be coaxial with the shaft 20 on the truck in whichever position the machine may be on the truck so that the clutch parts 21 and 22 can cooperate to effect truck propulsion and can be engaged with and disengaged from each other by endwise movement of the machine relative to the truck. Although it is preferred to arrange the shafts to be coaxial it will be understood that this is not an essential feature of a direct driving connection effected by endwise movement of the machine, for this may be effected by means of a sliding gear connection with the shafts out of line.

Figure 4 illustrates a truck in which the machine supporting platform is arranged to be raised and lowered by means of jacks 43 as in the aforesaid prior application; pivoted radius rods 44 being provided on each side of the platform to guide it and to enable the drive to be transmitted from the shaft 20 to the track wheels by means of suitable chain gear 45.

While I have in this application specifi-

cally described two forms which my invention may assume in practice, it will be understood that these forms of the same are shown for purposes of illustration and that the invention may be modified and embodied in various other forms without departing from its spirit or the scope of the appended claims.

I claim:

1. In a mining machine truck the combination with horizontal supports which support the machine in a working position in which it lies on its bottom or top lengthwise on the truck, of another horizontal support which is at a lower level than that of the other supports and is between them and can support the machine when it is horizontal but on its side.

2. A truck comprising the combination according to claim 1 and provided with propelling gear which is so arranged as to be directly engageable with a driving member on the machine when the said machine is in any of its aforesaid positions on the truck.

3. The combination with the subject-matter of claim 1 of clamping devices such as 10 arranged to embrace the machine when in position on its side on the truck and to be folded down into the channel when it is required to use the truck to support thereon the machine laid on its own top or bottom.

4. The combination with the subject-matter of claim 1 of clamping screws (13) so situated and arranged as to engage existing recesses (such as 14 provided for another purpose) in the sides of the machine when the said machine is on its top or bottom on the truck.

5. The combination with the subject-matter of claim 1 of a detachable loading and unloading slide and means on the truck (for example the parts 17 and 18) so situated in relation to the supports that are at different levels therein as to enable the said slide to be operatively connected at will either with the support at the higher or with that at the lower level so that the machine can be loaded to and unloaded from either level.

6. The combination according to claim 1 adjustable relatively to the track wheels, (for example by means of the jacks 43) into different horizontal planes.

7. For a mining machine having a plurality of surfaces on which it is adapted to be selectively supported and a swinging cutting member, a wheeled truck having a platform provided with a longitudinal channel arranged to receive and support the machine on its side supporting surface so that the cutting member can swing in a vertical plane for shearing, while portions of the platform on either side of the channel serve to support the machine on its top or bottom supporting surface so that the cutting member can swing in different horizontal planes for overcutting or undercutting.

8. A mining machine truck according to claim 7 wherein the channel is of such a depth that a driving member situated on the central longitudinal axis of the machine will be coaxial with a driven member on the truck when the machine is on its side in the channel, for the purpose described.

9. In a mining apparatus, a truck providing means for supporting a mining machine in working positions with either its top or its bottom surface horizontal, and also providing distinct means at a different level than said first mentioned supporting means for supporting the machine when it is horizontal but on its side.

10. In a mining apparatus, a truck providing means for supporting a mining machine in working positions with either its top or its bottom surface horizontal, and also providing distinct means at a different level than said first mentioned supporting means for supporting the machine when it is horizontal but on its side, and truck propelling gear for said truck including an element arranged to be directly engageable by a driving member on a mining machine when the machine is supported in any of the positions aforesaid on the truck.

11. In a mining apparatus, in combination, a truck providing means for supporting a mining machine in working positions with either its top or bottom surface horizontal and also providing distinct means at a different level than said first mentioned supporting means for supporting the machine when it is horizontal but on its side, said truck having propelling gear including a driving element so arranged as to be directly engageable by a driving member on a mining machine when the machine is supported in any of the positions aforesaid on the truck, and a mining machine supportable on said truck and having a power rotatable clutch element adapted to cooperate with said driving element and rotatable on the central longitudinal axis of the machine, the said axis of said machine lying in the same horizontal plane in either working position thereof.

12. In a mining apparatus, in combination, a truck providing means for supporting a mining machine in working positions with either its top or bottom surface horizontal and also providing distinct means at a different level than said first mentioned supporting means for supporting the machine when it is horizontal but on its side, said truck having propelling gear including a driving element so arranged as to be directly engageable by a driving member on a mining machine when the machine is supported in any of the positions aforesaid on the truck, and a mining machine supportable on said truck and having a power rotatable clutch element adapted to cooperate with

4
said driving element and rotatable on the central longitudinal axis of the machine, the said axis of said machine lying in the same horizontal plane in either working position thereof, and said clutch element and driving element having cooperating locating devices arranged to locate the driving and driven elements in mutually coaxial relation.

13. In a mining apparatus, in combination, a truck providing means for supporting a mining machine in working positions with either its top or bottom surface horizontal and also providing distinct means for supporting the machine when it is horizontal but on its side, said truck having propelling gear including a driving element so arranged as to be directly engageable by a driving member on a mining machine when the machine is supported in any of the positions aforesaid on the truck, and a mining machine supportable on said truck and having a power rotatable clutch element adapted to cooperate with said driving element and rotatable on the central longitudinal axis of the machine, said clutch element and driving element having cooperating locating devices arranged to locate the driving and driven elements in mutually coaxial relation and one of said elements having a part slid able in an axial direction and spring pressed toward one position thereof.

14. In a mining apparatus, a truck providing means for supporting a mining machine in a working position with a surface thereof substantially horizontal, and also providing a distinct support at a different level than said first mentioned supporting means for supporting the machine in a different working position with the surface aforesaid substantially vertical.

15. In a mining apparatus, a truck providing means for supporting a mining machine in a working position with a surface thereof substantially horizontal, and also provid-

ing a distinct support at a different level 45 than said first mentioned supporting means for supporting the machine in a different working position with the surface aforesaid making a substantial angle with its original position. 50

16. In a mining apparatus, a truck providing means for supporting a mining machine in a working position with either its top or its bottom surfaces horizontal, and also providing distinct means at a different 55 level than said first mentioned supporting means for supporting the machine when it is horizontal but on its side, the longitudinal axis of said machine lying in the same horizontal plane in either working position 60 thereof.

17. In a mining apparatus, a truck providing means for supporting a mining machine in a working position with a surface thereof substantially horizontal, and also 65 providing a distinct support at a different level than said first mentioned supporting means for supporting the machine in a different working position with the surface aforesaid substantially vertical, the longitudinal axis of said machine lying in the same horizontal plane in either working position 70 thereof.

18. In a mining apparatus, a truck providing means for supporting a mining machine in a working position with a surface thereof substantially horizontal, and also providing a distinct support at a different level than said first mentioned supporting 75 means for supporting the machine in a different working position with the surface aforesaid making a substantial angle with its original position, the longitudinal axis of said machine lying in the same horizontal plane in either working position thereof. 80 85

In testimony whereof I affix my signature.

EDWARD BUCKMASTER ROBINSON.
